(57) CLAIM

The ornamental design for a sushi serving device with integrated sauce dish, as shown and described.

DESCRIPTION

FIG. 1 is a first top perspective view of a first embodiment of a sushi serving device with integrated sauce dish, according to my new design;

FIG. 2 is a second top perspective view of the sushi serving device with integrated sauce dish shown in FIG. 1;

FIG. 3 is a bottom perspective view of the sushi serving device with integrated sauce dish shown in FIG. 1;

FIG. 4 is a left side elevational view of the sushi serving device with integrated sauce dish shown in FIG. 1;

FIG. 5 is a right side elevational view of the sushi serving device with integrated sauce dish shown in FIG. 1;

FIG. 6 is a top side view of the sushi serving device with integrated sauce dish shown in FIG. 1;

FIG. 7 is a bottom side view of the sushi serving device with integrated sauce dish shown in FIG. 1;

FIG. 8 is a front side elevational view of the sushi serving device with integrated sauce dish shown in FIG. 1; and

FIG. 9 is a rear side elevational view of the sushi serving device with integrated sauce dish shown in FIG. 1.

FIG. 10 is a first top perspective view of a second embodiment of a sushi serving device with integrated sauce dish, according to my new design;

FIG. 11 is a top perspective, enlarged view of the region 11 of FIG. 10;

FIG. 12 is a second top perspective view of the sushi serving device with integrated sauce dish shown in FIG. 10;

FIG. 13 is a bottom perspective view of the sushi serving device with integrated sauce dish shown in FIG. 10;

FIG. 14 is a left side elevational view of the sushi serving device with integrated sauce dish shown in FIG. 10;

FIG. 15 is a right side elevational view of the sushi serving device with integrated sauce dish shown in FIG. 10;

FIG. 17 is a bottom side view of the sushi serving device with integrated sauce dish shown in FIG. 10; FIG. 18 is a front side elevational view of the sushi serving device with integrated sauce dish shown in FIG. 10; and, FIG. 19 is a rear side elevational view of the sushi serving device with integrated sauce dish shown in FIG. 10. The broken lines in FIGS. 1, 2 and 6 illustrate an unclaimed design feature of the sushi serving device with integrated sauce dish and form no part of the claimed design.
